CARTON FOR CLOCK PARTS

Peter Norman Haward, London, England, assignor to
Thwaites & Reed Limited, London, England

Filed Dec. 23, 1968, Ser. No. 15,082

Term of patent 14 years

Int. Cl. D9—04

U.S. Cl. D9—195

FIG. 1.

FIG.2

FIG.4.

FIG.3.

FIG. 1 is a front elevational of a carton for clock parts showing my new design, the rear elevation being substantially plain and unornamented:

FIG. 2 is a side elevation thereof, the side opposite being identical thereto:

FIG. 3 is an end elevation, the end opposite being identical thereto.

FIG. 4 is a sectional view on the line 4—4 of FIG. 1.
I claim:

The ornamental design for a carton for clock parts, substantially as shown and described.
